D. Schilling, per
his Atty Albert W. Brown.

United States Patent Office.

D. SCHILLING, OF BROOKLYN, NEW YORK.

Letters Patent No. 83,215, dated October 20, 1868.

IMPROVEMENT IN WATER-CLOSETS.

The Schedule referred to in these Letters Patent and making part of the same.

To all whom it may concern:

Be it known that I, D. SCHILLING, of the city of Brooklyn, in the county of Kings, and State of New York, have invented new and useful "Improvements in Water-Closets, privies, and other similar places;" and I do hereby declare that the following is a full, clear, and exact description thereof, which will enable others skilled in the art to make and use the same, reference being had to the accompanying drawings, forming part of this specification.

The present invention consists in the combination, with a water-closet, privy, and other similar places, of a receptacle or receptacles for a deodorizing or disinfecting-medium, whether in the form of a powder or liquid, when such receptacle or receptacles is provided with an arrangement of mechanism by which the disinfectant contained in it can be discharged into the chamber or box surrounding the water-closet bowl or privy-seat, or into such bowl, &c., and thus, by being there exposed to the effluvia arising from the excrement within or discharged into the bowl or vault, cause the same to be thoroughly and effectually disinfected or deodorized.

In the accompanying plate of drawings, my improvements in water-closets, privies, &c., are illustrated,

Figure 1 being a vertical section of a water-closet seat and casing, taken in a direction from front to rear, and

Figure 2 a transverse vertical section, taken in the plane of the line $x x$, fig. 1.

A, in the drawings, represents a box or casing, of suitable shape to surround and encase a water-closet bowl, or an offal-pail or vessel, and leave a chamber or space, B, about the same, to which there is a floor, C.

D, a cover or lid to chamber B. This cover D is provided with a hole, E, similar to that found in water-closet and privy-seats, below which hole E the excre-

ment or offal-bowl is placed upon the floor C. The cover D is also hinged at its rear side, so as to be swung up for the removal of the offal-bowl, or for other purposes, and at its front side or edge F, rests upon the outer ends G of a lever-frame, H, that is hung by its cross-piece I to the rear side of the chamber or box B.

J, a spiral spring, on which the lever-frame H rests. K, a rod, connecting lever-frame H, upon its upper side, with a roller or drum, L, arranged in the throat M, to the lower end of a hopper, N, for the reception of the deodorizing or disinfecting-agent. This hopper is located above the water-closet seat, and the roller L, arranged in it, is at points O cut away or grooved, so that when turned by the depressing of the lever-frame, through the weight of the person upon the privy-seat, it will allow and carry through the throat of the hopper some of the disinfectant contained therein, this roller always closing the throat, except when operated as above stated.

Having thus described my improvements, I shall state my claim as follows:

What I claim as my invention, and desire to have secured to me by Letters Patent, is—

A water-closet, privy, or other seat, when provided with a receptacle or receptacles for a deodorizing or disinfecting-agent or agents, in combination with an arrangement of mechanism, substantially as herein described, by which such disinfectants can be discharged into the chamber or space about the bowl, &c., or into it, substantially as and for the purpose described.

The above specification of my invention signed by me, this 21st day of January, A. D. 1868.

D. SCHILLING.
